United States Patent Office

Des. 228,827
Patented Oct. 30, 1973

228,827

EXPANDED CEREAL FOOD PRODUCT

Peter A. Cammelot, Streamwood, Leroy F. Duvall, Barrington, and Kenneth L. Helmke, Elgin, Ill., assignors to The Quaker Oats Company

Filed Oct. 4, 1972, Ser. No. 298,778

Term of patent 14 years

Int. Cl. D1—02

U.S. Cl. D1—1

FIG. 1

FIG. 3

FIG. 2

FIG. 4

FIG. 5

FIG. 1 is a top view of an expanded cereal food product showing our new design;

FIG. 2 is a side view thereof;

FIG. 3 is a left-end view thereof;

FIG. 4 is a right-end view thereof; and

FIG. 5 is a bottom view thereof.

We claim:

The ornamental design for an expanded cereal food product, as shown.
